UNITED STATES PATENT OFFICE.

WILLIAM H. H. SISUM, OF BROOKLYN, NEW YORK.

ENDLESS-ROPE RAILWAY.

SPECIFICATION forming part of Letters Patent No. 295,446, dated March 18, 1884.

Application filed October 25, 1883. (No model.)

To all whom it may concern:

Be it known that I, WILLIAM H. H. SISUM, of Brooklyn, in Kings county, and the State of New York, have invented a certain new 5 and useful Improvement in Endless-Rope Railways, of which the following is a specification.

The object of my improvement is to provide a simple and effective mechanism whereby the rope may be gripped from a car and the car 10 gradually started.

I will describe in detail a railway embodying my improvement, and then point out the improvement in claims.

In the accompanying drawings, Figure 1 is 15 a plan of an endless-rope railway and a car-truck fitted with mechanism embodying my improvement. Fig. 2 is a sectional elevation of the same, taken on the plane of the dotted line xx , Fig. 1. Fig. 3 is a front view of the 20 mechanism with which the car is fitted. Fig. 4 is a sectional view of a portion of the latter. Fig. 5 is a side view of grip mechanism of modified form. Fig. 6 is a front view thereof. Fig. 7 is an enlarged transverse section of one 25 of the grip-pulleys; and Fig. 8 is a transverse section of the other grip-pulley.

Similar letters of reference designate corresponding parts in all the figures.

A designates rails, which may be of any construction suitable for supporting a car, and laid in the usual or any other approved manner.

B designates an endless rope or cable, which travels between the rails, guide-pulleys being employed to guide it, and any suitable means 35 to drive it.

C designates the frame of a car-truck, C' the wheels thereof, and C² the axles of the wheels. The wheels are rigidly affixed to their axles, as is usual in railway-cars. The axles may be 40 journaled in the truck-frame in any suitable manner.

On one of the axles C² are rigidly fastened two clutch-pieces, D D', having reversely-arranged ratchet-teeth. Between these clutch-pieces D D' a clutch-piece, D², is supported by the same axle in such manner that it may be shifted longitudinally into contact with either of the clutch-pieces D D'. At its end the clutch-piece D² is provided with ratchet-teeth arranged reversely to the ratchet-teeth of the adjacent clutch-pieces D D', so that when rotated in either direction it may be engaged with one

or the other of the clutch-pieces D D', to rotate them, and consequently the axle to which they are affixed, either one way or the other, 55 as may be desirable.

A lever, D³, is fulcrumed to a hanger, D⁴, extending from a platform, E, in the car of which the truck described forms part. The lower end of this lever is forked or bifurcated, 60 so as to embrace the clutch-piece D², and has pins that enter a circumferential groove in this clutch-piece. The upper end of this lever extends through a slot in the platform E. By oscillating the lever the clutch-piece D² may 65 be shifted longitudinally, and, owing to the manner in which the lever is connected to this clutch-piece D², the lever will not interfere with the rotation of the clutch-piece. The clutch-piece D² has combined with it a gear-wheel, 70 F. This gear-wheel and the said clutch-piece are connected, so as to turn in unison. As here shown, the gear-wheel has a long hub, a, extending from each side of it. The clutch-piece D² is made in two sections, mounted on 75 the hubs—one on each side of the gear-wheel—and bolts b extend through the two sections of the clutch-piece and the gear-wheel. In effect I therefore make a double clutch-piece, D², forming one structure, and although it is supported directly upon the hubs of the gear-wheel, yet it is indirectly supported on the axle upon which the gear-wheel is arranged. These parts may be combined in other ways to attain the same result. 85

G designates a grip-pulley, which is rigidly affixed to a shaft, G', journaled in a frame, G². The side pieces of the frame G² are mounted on the axles C² in such manner that they will not interfere with the rotation of the latter. 90

H designates another grip-pulley, arranged in line with the grip-pulley G, and having its shaft journaled at one end in a lever, H', that is hung on the shaft G', as shown in Figs. 1, 2, and 3, and on a stud, I, as shown in Figs. 5 and 6. I prefer to make each of the pulleys G H of two lateral sections, c c', (see Figs. 7 and 8,) secured together by bolts or screws d, and having at the circumference materials which will generate much friction. As shown, 95 I so shape the sections c c' at their circumference that a deep rectangular groove will be formed there. In this groove I fit a band, e, of india-rubber, made rectangular in the cross-

section, and into this band I fit a number of rings or bands, *f*, of leather, rawhide, or other material. The facings formed of these materials will grip the endless rope or cable without liability of injuring it. At the periphery 5 the facings are hollowed out to conform to the endless rope or cable. The india-rubber band *e* is held in place by lips *g*, extending from the lateral sections *e' e'* of the pulleys. The upper 10 end of the lever *H'* has fastened to it a cord or chain, *J*, which is secured to and wrapped around a rod or windlass, *K*. By turning this windlass, and thereby drawing upon the cord or chain *J*, the lever *H'* will be canted or tilted, so that the pulley *H* will be drawn up into 15 a position in which it will bear tightly upon the endless rope or cable and cause the latter to bear forcibly against the pulley *G*. The lever may be canted in the reverse direction 20 by means of a cord or chain, *J'*, and another windlass arranged at the other end of the car. The shaft *G'* has rigidly affixed to it a gear-wheel, *L*, that engages with the gear-wheel *F*.

To cause the car to derive motion from the 25 endless rope or cable, the clutch-piece *D*² is shifted into engagement with the clutch-piece *D*, and the lever *H'* is canted to cause the grip-pulleys and the endless rope or cable to forcibly impinge. The grip-pulleys are thus caused 30 to rotate, and thereupon the gear-wheel *L* transmits motion through the gear-wheel *F* to the axle, onto which the gear-wheel *F* is affixed. The grip-pulleys continue to act in this 35 way until the gear-wheel *F* has acquired its maximum speed. When this gear-wheel has attained such speed, it rotates with sufficient rapidity to cause the clutch-piece *D*² to move faster than the clutch-piece *D*, whereupon the clutch-piece *D*² will be thrown out of engagement 40 with the clutch-piece *D*. The motion of the car will have been gradually augmented until by this time its momentum will be such that its drag on the rope or cable will be insufficient to cause the rotation of the grip-pulleys. The grip-pulleys will then form a 45 secure grip, whereby the car will be propelled. If desirable, the lever may be canted farther after the car gets under way, so as to grip the endless rope or cable more tightly. When the 50 lever *H'* is hung upon the stud *I* eccentrically to the pulley *G*, the pulley *H* may be made to grip the rope or cable very tightly between it and the pulley *G*. When the car is to be stopped, the cord or chain *J* is slackened and 55 brakes of the usual or any suitable kind are applied to the wheels of the car. When the car is to be propelled in the reverse direction upon another portion of the endless rope or

cable, the clutch-piece is shifted into engagement with the clutch-piece *D*' and the cord or chain *J'* is tightened, so as to cant the lever *H'* in the reverse direction. The endless rope or cable is to be lifted over and off the pulley *H* to engage it with such pulley and disengage it therefrom. 60

It is advantageous that the frame *G*² should be supported upon the car-axles instead of on the body of the car, as it will not then be affected by the varying position or the jolting of the body of the car. 65

What I claim as my invention, and desire to secure by Letters Patent, is—

1. The combination, with a car, of grip-pulleys adapted to impinge upon a rope or cable, and wheels serving to derive motion 75 from one of the pulleys and transmit it to one of the axles of the car, so as to start the car gradually, substantially as specified.

2. The combination, with a car, of a grip-pulley supported on a shaft provided with a 80 wheel engaging with another wheel mounted on one of the axles, another grip-pulley supported on a lever adapted to be adjusted into a position which will enable it, in conjunction with the grip-pulley first named, to grip a rope 85 or cable, substantially as specified.

3. The combination, with a car, of a grip-pulley supported on a shaft provided with a wheel engaging with another wheel mounted on one of the axles, another grip-pulley supported on a lever, and means whereby the 90 lever may be swung in either direction to cause the grip-pulley which it supports, in conjunction with the grip-pulley first named, to grip a rope or cable, substantially as specified. 95

4. The combination, with a car, of grip-pulleys, means whereby the grip-pulleys may be made to grip a rope or cable, a wheel on the same shaft as one of the grip-pulleys, a wheel on one of the axles of the car, through which motion is transmitted to this axle, clutch-pieces rigidly affixed to this axle, and another clutch-piece locked to the wheel, through which motion is transmitted to this 100 axle and adapted to be shifted into engagement with either of the clutch-pieces that are affixed to this axle, substantially as specified. 105

5. The combination of an axle, *C*², clutch-pieces *D* *D'* *D*², gear-wheel *F*, shaft *G'*, gear-wheel *L*, grip-pulley *G*, lever *H'*, and grip-pulley *H*, substantially as specified. 110
